UNITED STATES PATENT OFFICE.

MORRIS MARTIN, OF MALDEN, MASSACHUSETTS, ASSIGNOR TO THE MUNICIPAL SIGNAL COMPANY, OF PORTSMOUTH, NEW HAMPSHIRE.

MUNICIPAL SIGNALING.

SPECIFICATION forming part of Letters Patent No. 380,655, dated April 3, 1888.

Application filed July 31, 1886. Serial No. 209,661. (No model.)

To all whom it may concern:

Be it known that I, MORRIS MARTIN, of Malden, Middlesex county, State of Massachusetts, have invented an Improvement in Municipal Signaling Apparatus, of which the following description, in connection with the accompanying drawings, is a specification, like letters on the drawings representing like parts.

10 My invention relates to municipal signal apparatus which may be used as an auxiliary to the police service of a city or town by establishing communication between a main office or police-station and sub stations or signal-boxes on the streets.

15 The object of the present invention is to provide a simple and inexpensive apparatus that will meet all the requirements for service of this kind, the said apparatus containing 20 means by which authorized citizens can summon police aid to the boxes and means for indicating which citizen has transmitted a call, so as to deter citizens from transmitting unnecessary calls. The signal-boxes also contain 25 telephones for the purpose of affording telephonic communication between the main office and the officers or other parties authorized to open the boxes, and they also contain means by which an officer on coming to a box can 30 ascertain directly without opening the box whether or not anything is wanted of him at the main office. The fact that the office may at any time be signaled from the main office is an inducement to the officer to visit the boxes 35 regularly, as he is aware that if he fails to respond to a signal that may be awaiting him his neglect will be discovered.

40 The invention consists, mainly, in the novel construction and arrangement of the circuit and instruments therein and mechanical appliances for operating said instruments by which the various objects are attained.

45 Figure 1 is a front elevation of a signal-box forming part of an apparatus embodying this invention; Figs. 2, 3, and 4, details showing the construction and operation of the key or device by which citizens provided with said keys can transmit the signal or call to the main office without opening the signal-box; Fig. 5, 50 a detail of an officer's signaling-key; Fig. 6, a detail of the device for operating a telephone-

call at a box, and Fig. 7 a diagram showing the arrangement of the circuit and instruments therein.

The signal-box *a*, which may be of any suitable or usual construction resembling the well-known fire alarm telegraph-boxes, contains an automatic signal-transmitting device, *b*, which may consist of a break-wheel and contact-spring operated by a clock-work or motor precisely like those employed in the well-known fire-alarm and district-telegraph systems, the said break-wheel being notched to produce breaks in the circuit controlled by it, and thus making a number-signal corresponding to each 65 box and showing the locality to which assistance is to be sent, in the same manner as in fire-alarm telegraphs.

The construction of the break-wheel motor, being well known, is not shown in detail; but 70 the means for winding and operating the said motor is believed to be novel.

The actuating-shaft *c*, that is acted upon by the motive weight or spring and transmits the motive power to the clock-work by means of 75 a ratchet and pawl in the usual manner, is provided with an arm, *d*, which, when pressed the proper amount, moves the ratchet ahead one tooth or notch with relation to the pawl and winds the spring, so that when the said arm *d* 80 is released it will be moved back by the spring and turn the train of wheels with it a sufficient amount to cause one or more complete rotations of the break-wheel, the said arm *d* thus being like the usual crank or winding handle 85 of a district-telegraph box. The said arm *d* is engaged by a projection, *e*, on a slide-bar, *e'*, which may be provided with a finger-piece, *e''*, to be engaged by the operator when the box-door is open, and is also connected by a link, 90 *e''*, to one arm of a lever, *f*, pivoted at *f'*, and having its other arm, *f''*, made cam-shaped and located over a key-hole, *g*, in the box in such position that a key having a bit of proper length when inserted in the said key-hole and 95 rotated will move the lever and thus depress the slide-bar *e'*. As the arm *d* moves in the arc of a circle, while the engaging projection *e* moves in a straight line, the said projection, after a certain movement which is sufficient to advance the ratchet of the motor one tooth or notch, will disengage the said arm *d* 100

and permit it to run back with the motor during the rotation of the break-wheel. In order to prevent the winding-arm *d* from being acted upon during its return movement, and thus 5 checking the movement of the motor and interfering with the signal, the winding slide-bar *e'* is locked during the return movement of the arm *d* by a locking device, shown as a sliding bolt, *h*, acted upon by a spring, *h'*, 10 which throws it over the upper end of the slide-bar *e'* when the latter is depressed, thus preventing return movement of the said slide-bar until released by said locking device, which takes place only when the arm *d* has completed 15 its return movement, just at the end of which an arm, *d'*, thereon acts upon the locking device *h* and disengages it from the slide-bar *e'*, which is then returned by a spring, *e'*, to its normal position. In order to permit the pro- 20 jection *e* to pass the arm *d* in the return movement of the slide-bar *e'*, the said slide-bar is arranged to have a sufficient lateral movement in its guides *e*⁵, and is acted upon by a spring, *e*⁶, that throws the projection *e* into engagement with the arm *d* after the projection has 25 passed the said arm in its upward movement.

The winding-lever *f* is so arranged with relation to the key-hole *g* that a key of proper size to fit the said key-hole, having a plain bit, 30 will operate the said lever and wind and release the motor; but a key having a shorter bit will not produce sufficient movement to wind the motor, but will merely spring the arm *d* down part way and then release it again. 35 It is intended to distribute keys to responsible citizens and to number each key thus given out and make a record of the number and name of the person to whom the key is given.

In order to show by which key an alarm 40 has been transmitted, the bits of the said keys are made in two parts, as shown in Figs. 3 and 4, the end of the bit being made separately from the body, connected therewith by a dovetail or similar joint that will permit the end 45 portion, *k'*, to slip out from the main portion *k* by a movement parallel with the shank or spindle of the key *K*. Both the main portion of the key and removable end portion, *k'*, of its bit bear the registered number of the key, as 50 shown, and it requires the combined length of both parts of the key to operate the lever *f* so as to wind the box. At the key-hole the box is provided with a stop, *m*, shown as a pivoted spring-pressed piece which yields to 55 permit the insertion of the entire key into the box, and then springs up behind the removable portion *k'* of the key-bit, so that when the key is withdrawn the said portion of the bit will be stripped off from the main portion and 60 left in the box, thus indicating which key has been used, and also disabling the said key, so that it cannot again be used until the removable indicating portion is replaced. The key is not, however, disabled until it is withdrawn 65 from the box, and may be used to repeat the signal as often as desired.

If a citizen after transmitting a call waits

without withdrawing the key until an officer responds to the call, the officer can open the box and release the removable or indicating portion of the key, or if the key has already been removed from the box the indicating portion may be taken from the box and returned to the key-holder.

The herein-described method of leaving a portion of the key in the box to indicate which key has been used, and at the same time disabling the key, has several important advantages over the method in which the entire key is retained in the box until released by an officer provided with means for effecting such release. When the entire key is retained and no means are provided for the prevention of breaking in upon a message, an evil-disposed person might, by turning the key during the transmission of the message, break up or distort the said message so that it could not be read correctly, while by the key of the kind herein shown the citizen, after he has once turned the key to send the message, can at the same time remove and disable the key so that no one can subsequently use it.

The signal box *a*, in addition to the automatic transmitter for telegraphic messages just described, contains a signal receiving instrument, *S*, (shown as a tap-bell,) and a telephone, *T*, which may be normally shunted by its supporting-hook *t*, in the usual manner; and the box also has a circuit-closer, *p*, preferably operated by a button, *p'*, from the outside of the box, for the purpose of operating the signal *S*, as hereinabove described. The box contains a circuit-breaker, *u*, which is operated when it is desired to signal the main office or call the attendant there to the telephone without sending in the number of the box.

The operation of the parts for transmitting and producing the signals may be best understood by reference to Fig. 5, that shows in diagram the circuits and instruments therein.

The main circuit is wholly metallic and connected at 2 with one pole of the main battery *B*, from which it passes through a receiving-relay, *r*, that controls a local circuit containing a register, *R*. The relay *r* also controls an indicating-instrument, *S*², which may be a vibrating bell, that when once set in operation by the closing of its circuit by the relay *r* when the main line is once broken closes the local circuit through its actuating-magnet, and thus remains in operation until stopped by the attendant. From the relay *r* the line is continued, as shown at 3, to the different boxes or stations, where it includes the break-wheels *b'* and telephones *T* when not shunted by their gravity-switches *t*, and returns to the other pole of the main battery, as shown at 4. The actuating-magnet *n* of the signal *S* is in a normally-open branch, 5, from the main line 3, the said branch containing the circuit-closer *p*, by which it may be connected with the ground. If one of the ground branches containing the magnet *n* of the signal *S* is closed, but the line is then grounded at no other point,

- no effect is produced on the said signal S. If, however, the attendant at the main office wishes to summon an officer, he will place a ground-connection on the line, preferably by a 5 grounded branch, 7, which is connected with the main line at one side of the main battery B, and includes a switch, s, and, preferably, an alarm-instrument, S³, which may be a vibrator, the armature of which vibrates at such 10 rate that the armature of the tap-bell S will naturally accompany it when both are in circuit together, as is the case when both earth branches 5 and 7 are closed at the same time. The closing of the earth branch 7 by the attendant at the main office will not affect the 15 line or instruments therein as long as all the other branches remain open, but as soon as an officer arrives at one of the boxes and closes the earth branch by the push-button p' a ground-circuit will be afforded including the magnets of both instruments S and S³, which will both be set in operation, thus indicating to the officer at the box that the attendant at the main office desires to communicate with him, and also indicating to the attendant at the main office that the officer has just arrived at a box and received his signal, and both will immediately proceed to the telephone. Should two officers 20 happen to close their earth branches simultaneously when the branch 7 at the main office was not closed, they would complete an earth-circuit through the signaling-instruments S at both boxes, but the pulls would only give a single tap, so that the officers would know that 25 they were not signaled from the main office. If necessary, resistance will be placed in the main line, as shown at R', beyond the junction of the earth branch 7, in order to cause a sufficient portion of the current to pass through 30 the earth-circuit to operate the signals S and S³. It may be desirable for the officers to summon aid without opening the box, and for this purpose they will also be provided with keys K', (see Fig. 5,) to operate the pull-lever f, the 35 same as the citizens' keys K, and as there is no need of leaving a record when the box is operated by an officer, and as the officer's key should never be disabled, it need not have a detachable bit; and in order to permit the key 40 to be readily withdrawn the bit is beveled, as shown at k³, Fig. 5, so that it will depress the catch-piece m, and may be removed without difficulty, and also without disabling it for future use. 45 The officer may sometimes desire to communicate with the main office by telephone without summoning aid, and the boxes are provided with means for operating a signal which will be known as a "telephone-call." 50 This is shown as effected by the circuit-breaker u, included in the main circuit, the movable member of which circuit-breaker is normally pressed by a spring, u', against the co-operating stationary member, and is actuated to produce 55 a momentary break in the circuit by a push-button, u², the shank of which has a sliding movement in a guide, u³, and is pro-

vided with a pivoted cross piece or lever, u⁴, one arm of which is arrested by a stoppin, u⁵, at the time that the opposite arm engages the movable member of the circuit-breaker, so that as the button u² is pressed farther in, the end of the cross-piece carries the movable member of the circuit-breaker away from the stationary member for a moment, 70 breaking the circuit, and then passes by the said movable member, which is at once restored to the normal position, closing the circuit, by the spring u'. When the push-button is released and returned to its normal position by 75 a spring, u⁶, the cross-piece turns on its pivot to permit its end to pass the movable member of the circuit-breaker, which it does without again breaking the circuit. The depression of the push-button u² thus causes a single break 80 in the circuit of short duration sufficient to act on the relay r at the main office and set the signal S² in operation; but as the operation of said signal will not be accompanied by a message on the register R it will be understood as 85 a call to the telephone and not a call for aid. 90

The telephonic instruments at the main office are not shown, as they are of usual character, and may be switched into or out from any of the circuits coming into the office in any 95 usual manner.

The usual magneto-telephones may be employed at the boxes and used both for transmitting and receiving, thus avoiding the necessity of maintaining a local-battery circuit 100 at each box.

Instead of placing the break-wheel b' directly in circuit, as shown, it may be in a branch of low resistance around a considerable resistance, (indicated in dotted lines at R², Fig. 7,) and thus operate by changing the current strength without wholly opening the circuit, and in such construction the circuit-breaker u might be in the same low-resistance branch around the resistance R² as the break-wheel b', or it might be, if desired, in the main circuit and operate a second relay at the main office not affected by the changes in the current strength controlling a local circuit containing an indicating-instrument similar to the one S². All such arrangements are well known and not specifically claimed as a part of the present invention, which consists, mainly, in the means for operating the transmitter-motor and in the arrangement of the signaling-instruments in the earth branches. I wish it to be understood that I consider any of the well-known transmitting devices having a notched or equivalent circuit-controlling surface and means to actuate it or its co-operating member, so as to automatically produce a definite series of changes in circuit, to be equivalent of the break-wheel and motor, which is merely shown as illustrating a simple, convenient, and familiar form of automatic transmitter. 125 130

I claim—

1. A signal-box containing the following elements in combination: an automatic transmitter having a circuit-controlling surface and

an actuating-motor, a winding device for said motor, an actuating device for the said winding device, arranged with relation thereto as described, whereby it operates the winding device to wind and then release the motor, and a locking device co-operating with said actuating device and winding device, as described, whereby the actuating device is engaged when the winding device is released and retained inoperative while the motor is running, substantially as described.

2. A signal-box and automatic transmitting device therein, combined with a key having a detachable indicating portion and a catch for said detachable portion, whereby the latter is removed from the key when the key is withdrawn from the box, the said key, when in the box, engaging and operating the automatic transmitting device, substantially as described.

3. A signal-box and automatic transmitting device therein, combined with a key composed of a main portion and detachable indicating portion co-operating with the transmitting device, as described, the entire key being capable of operating the transmitting device, while the main portion alone is insufficient to operate the transmitting device, and a catch that retains the detachable portion of the key when the main portion is removed from the box, substantially as described.

4. In a municipal signal system, the combination, substantially as described, of an electric circuit, a main office or receiving-station containing a receiving-relay and an indicating-signal, a series of signal-boxes each containing a signal-transmitting device, and also an independent hand-operated circuit-controlling device consisting of two pivoted levers, a contact-point for each lever, and a push-button to move the other lever in contact with its contact-point and to disengage the first lever from its contact-point, substantially as described.

5. In a municipal signal system, the combination, substantially as described, of an electric circuit, a main office or receiving-station containing a receiving-relay, a register, and an indicating-signal, a series of signal-boxes each containing a signal-transmitting device, and also an independent hand-operated circuit-controlling device consisting of a lever, u , spring u' , and a push-button having a pivoted lever, u'' , and spring.

6. In a municipal signal system, the combination, substantially as described, of an electric circuit, a main office or receiving-station containing a receiving-relay, a register, and an indicating-signal, a series of signal-boxes

each containing a signal-transmitting device, and also an independent hand-operated circuit-controlling device accessible from the exterior of the box, as described, said circuit-controlling device being constructed and arranged to momentarily change the condition of the circuit when operated.

7. A telegraph apparatus comprising a series of stations and metallic circuit connecting the same and normally-open earth branches at the said stations, and a switch at one station, by which one of the earth branches at said station may be closed, and normally-open circuit-closers and signaling-instruments in the earth branches at the other stations, whereby an earth-circuit may be established through the said signaling-instrument if the switch is closed at the other station, substantially as and for the purpose set forth.

8. A telegraph apparatus comprising a main station and series of sub-stations and metallic circuit connecting the same, combined with normally-open earth branches at all the said stations and a switch and vibrator in the earth branch at the main station, and a normally-open circuit-closer and tap-bell in the earth branches at the sub-stations, substantially as and for the purpose described.

9. A signal-box and a transmitting device therein, combined with a key for effecting the operation of the transmitting device, said key having a detachable portion which is left in the box when the key is withdrawn therefrom, substantially as described.

10. A signal-box and a transmitting device therein, combined with a key for effecting the operation of the transmitting device, said key being numbered and having a corresponding numbered detachable portion which is left in the box when the key is withdrawn, whereby a particular key which has been employed to operate the transmitting device may be detected, substantially as described.

11. A signal-transmitter, a motor mechanism, a winding device for the motor mechanism, and an actuating device for the winding device, combined with a spring-controlled slide-bar, h , which engages and holds the actuating devices during the time the motor is running, substantially as described.

In testimony whereof I have signed my name to this specification in the presence of two subscribing witnesses.

MORRIS MARTIN.
